ELECTRICAL CONNECTOR

Nicholas Gust Gekas, Harrisburg, and Boyd Hutchinson Cree, Camp Hill, Pa., assignors to AMP Incorporated, Harrisburg, Pa.

Filed May 5, 1971, Ser. No. 140,412

Term of patent 14 years

Int. Cl. D13—03

U.S. Cl. D26—1 C

FIG. 1 is a perspective view of an electrical connector showing our new design;

FIG. 2 is a front elevational view;

FIG. 3 is a side plan view, the opposite side being substantially a mirror image thereof;

FIG. 4 is a back elevational view;

FIG. 5 is a top plan view; and

FIG. 6 is a bottom plan view.

We claim:

The ornamental design for an electrical connector, as shown and described.
